REFRIGERATION MEANS AND METHOD

Viggo V. Torbensen, Cleveland, Ohio

Application April 5, 1939, Serial No. 266,037

9 Claims. (Cl. 62—116)

The present invention pertains to improvements in refrigeration means and method.

An object of the invention is to provide an improved method of cooling a refrigerator without forming ice therein.

A further object is to provide an improved refrigerating device having two compartments of different temperature for properly preserving articles of different nature, the nature of the article placed in one compartment and the temperature of said article partially determining the final temperature in that compartment.

Another object is to provide a refrigerator of the above character having a compartment wherein frozen articles may be kept from melting or from losing their frozen condition.

Another object is to provide a refrigerator wherein de-frosting is minimized, wherein condensation is kept low and proper humidity maintained.

A further object is to provide a refrigerator adapted to receive pre-frozen ice cubes and to preserve them while cooling the refrigeration chamber with minimum operation of the refrigerating machine.

A still further object is to provide a device of the above character which is simple, low in cost, and economical in operation.

Other advantages and features of the invention will become evident during the course of the following description in connection with the accompanying drawing, in which—

Figure 1 is a horizontal sectional view of a refrigerator embodying the invention, the section being taken in the plane 1—1 of Figure 3, with a portion of the horizontal partition broken away to more clearly disclose the evaporator structure;

Figure 2 is a vertical partial section on the lines 2—2 of Figures 1 and 3, together with diagrammatic connections to a suitable refrigerating machine;

Figure 3 is a vertical sectional view on the line 3—3 of Figure 1;

Figure 4 is an enlarged detail sectional view of the evaporators and related apparatus;

Figure 5 is a detail side elevation of an alternative form of evaporator structure; and

Figure 6 is a fragmental view of an alternative inlet header structure.

Referring to the drawing, the numeral 10 generally denotes a refrigerator cabinet having an insulated main portion 11. A similarly insulated cover plate 12 forms the top of the cabinet 10, the plate 12 resting by gravity on a resilient in-

sulating gasket 13 supported on the upper rim of the main portion 11, Figures 2 and 3.

A horizontal panel 14 is suspended from the top plate 12 by means of bolts 15 and clamps 16, spacer members 17 being clamped between panel 14 and the under surface of the plate 12, as shown in Figure 2. The panel 14 is of such size as to fit snugly in the inside of the cabinet 10, thus forming a partition between an upper chamber 18 and a lower chamber 19 therein.

Two vertical metal plates 20 and 21 are secured to the bottom of the panel 14 by means of screws 22 passing through the latter and engaging a channel member 23, as shown in Figure 4. The plates 20 and 21 have, respectively countersunk therein, uniplanar evaporator members 24 and 25, each evaporator member being formed of a continuous length of tubing with return bends and parallel straight portions between bends. The tubing of members 24 and 25 protrudes beyond the surfaces of plates 20 and 21, and the latter are drawn toward each other by screws 26, causing the members 24 and 25 to be flattened against each other throughout their entire lengths of contact between the plates. This structure provides wide firm contact between the evaporator members and between the latter and the plates 20 and 21, promoting good and uniform heat transfer relations between these parts as hereinafter set forth in the description of the operating characteristics.

The plates 20 and 21 are provided with a plurality of laterally extending vertical fins 27, these fins being either cast integrally with plates 20 and 21 or fastened thereto by any suitable means in heat-transfer relation.

A rectangular baffle 28, open at the bottom, is secured to the panel 14 and surrounds the described sub-assembly of evaporator members 24 and 25, plates 20 and 21, and fins 27. Lateral openings 29 are provided in the baffle 28 to permit air circulation through the interior thereof as hereinafter set forth.

A flat metal pan 30 is secured on the top of low walls 30a extending upward from the panel 14. Uniplanar evaporator members 31 and 32 of general construction similar to members 24 and 25, are secured flat on the bottom of the pan 30, preferably by soldering or the like to promote good heat conduction. A perforated tray 33 for ice cubes fits in the pan 30 and may be removed therefrom through a door 34 (Figure 3), in the front of the cabinet 10.

Perforations 35 are provided in the pan 30, and similar perforations 36 are provided in the

panel 14 immediately above the fins 27 as shown in Figure 4, wherein the sectional plane is jogged as indicated in Figure 3 in order to show both the perforations 36 and the clamping screws 26 5 in full section.

The inlet ends 37, 38, 39 and 40, respectively, of evaporator members 24, 25, 31 and 32 are all preferably connected to a common inlet header 41, Figures 1 and 3. Similarly, the outlet or 10 suction ends of all the above evaporator members are preferably connected to a common suction header 42.

In Figure 2, the numeral 43 generally denotes a refrigerating machine of any suitable type, 15 herein represented diagrammatically as comprising the usual motor 44, compressor 45, condenser 46, and liquid receiver 47. The receiver 47 is connected via a liquid line 48 and an expansion valve 49 with the inlet header 41, while a suction line 50 connects the suction header 42 with the compressor 45 in the usual manner. The refrigerating machine may be provided with any suitable type of cycling control means, herein 20 illustrated as a thermostatic switch 51 having its 25 feeler bulb 52 clamped to the evaporator member 32 near the outlet end thereof.

The operation is as follows:

The expansion valve 49 which admits refrigerant to the four evaporator members 24, 25, 31, 30 and 32, through the inlet header 41, is preferably set to maintain a refrigerating temperature at or near the freezing temperature of water. As the refrigerating machine operates, all evaporator units receive liquid refrigerant at the 35 same pressure, evaporate it at the same temperature, and deliver the resultant vapors via the common header 42 and suction line 50 to the compressor 45.

The upper two evaporator units 31 and 32, 40 which obviously function as a single unit and for simplicity may consequently be hereinafter referred to collectively as the upper evaporator, refrigerate the upper chamber 18 together with the pan 30 and tray 33. Similarly the lower units 45 24 and 25, functioning as a single unit which may hereinafter be collectively termed the lower evaporator, refrigerate the plates 20 and 21, the fins 27 and the compartment 19.

As pointed out above, the refrigerating temperature of the upper and lower evaporators is the same. The upper compartment 18, however, is comparatively small and low, and the structures therein are so formed and disposed that convective circulation of air is minimized.

Furthermore, the evaporator members 31 and 32 are separated from the panel 14 by a substantially dead air space, the perforations 36 being too small to allow any appreciable circulation therethrough, and due to the general lack 60 of circulation noted, but little heat enters the body of the chamber 18. Consequently, as the refrigerating machine operates under control of the switch 51, the chamber 18 acquires a general temperature differing but little from that of the upper evaporator itself, this normal general temperature of chamber 18 being substantially at or slightly above the freezing point of water.

The tray 33 is removed through the door 34, 70 pre-frozen ice cubes 53—that is, cubes from an outside source, which are a well-known article of commerce—are placed therein, and the tray of cubes is replaced on the pan 30.

As the cubes 53 are already frozen, practically the only refrigeration necessary to preserve them 75 is that required to overcome the heat leakage

of the chamber 18, and this, as noted, is very small.

Commercial ice cubes are frequently heavily sub-cooled to avoid meltage in shipment, and when this is the case, the cubes themselves furnish a certain amount of initial cooling effect below the freezing point which further assists in stabilizing the temperature of the chamber 18. During operation of the refrigerating machine 43, the cubes 53 may receive preservative 10 refrigerating effect by direct conduction from the evaporator units 31 and 32 through the pan 30 and the bottom of the tray 33, while between 15 runs of the machine the general low temperature of the chamber 18 continues the preservative conditions. If at any time the temperature in chamber 18 rises sufficiently to permit slight meltage of the cubes, this meltage itself extracts heat from the surrounding media and thereby assists in maintaining the general preservative 20 temperature near the freezing point of water, as previously set forth.

During such slight meltage, the evolved water drains through perforations 35 and 36 and drips on the fins 27 where it assists humidification in 25 the lower chamber 19 as hereinafter set forth. Similarly, any condensate or even meltage from possible occasional light frost formation on the evaporator members 31 and 32, also drips through the perforations 36 to the fins 27.

In the lower compartment 19, the openings 29 in the baffle 28 permit and assist circulation of air, the normal paths of circulation being upward outside the baffle, inward through the openings 29, and downward along the fins 27 and 35 plates 20 and 21.

The refrigerating temperature in the evaporator members 24 and 25 is the same as that in the upper evaporator, namely, at or near 32° F., but due to the large heat absorbing surface provided by the fins 27 and plates 20 and 21 in proportion to the inside surface of the lower evaporator members 24 and 25, and also due to the comparatively large amount of material and surface to be cooled in chamber 19 and the free 45 circulation of air therein as noted, the temperature of the heat absorbing surfaces normally is considerably above the freezing point of water.

The even distribution of heat absorption is promoted by the wide and intimate contact between the evaporator units and the plates 20 and 21.

Consequently the undue formation of frost on the main heat-absorbing surfaces is eliminated, avoiding serious dehydration of the air and food in the storage chamber. Such condensation of moisture as occurs on the fins 27 and plates 20 and 21 is largely retained thereon where it may readily be picked up again by the circulating air during the idle periods of the refrigerating cycle, thus promoting proper humidity of the air. This humidifying surface moisture is augmented by any drip of water on the fins 27 through the perforations 36 as previously set forth.

With any given cycling operation of the refrigerating machine 43, the normal temperature in the chamber 19 is largely determined by the temperature and heat emitting capacity of the material, such as food, placed therein, and also naturally by the frequency of withdrawals and replacements of materials.

Obviously, the cycling operation of the refrigerating machine 43 may be set as desired by means of the switch 51 or its equivalent. It will 75

be seen from the previous description, however, that the temperatures and operating conditions in the main chamber 18 have negligible effect on the functioning of the upper ice storage chamber 5 18, wherein the uniform temperature at or near 32° F. is maintained jointly by the upper evaporator and by the stored ice itself.

The foregoing description makes clear that the method and apparatus comprising the invention 10 provide a two-temperature refrigerator operating from a common source of refrigeration without dual controls or like complications, the refrigeration being furnished to both evaporators at a single advantageous temperature. The economy 15 of power made possible by the invention is especially large in comparison with the usual systems in which the apparatus is required to freeze ice cubes. While the freezing point of water is approximately 32° F., in order to actually freeze 20 any usable quantity of ice in reasonable time it is necessary to provide an evaporator temperature much lower than 32° F. When, as in common small refrigerator practice, the ice freezing function is combined with the principal function of 25 food preservation, the necessary low evaporator temperature gives rise to well-known difficulties with frosting and necessary defrosting, dehydration of food, and comparatively long operation of the refrigerating plant necessary to extract first 30 the sensible heat and then the latent heat of the water being frozen.

Furthermore, the necessity of producing the low freezing temperature forces the refrigerating plant to operate in a range much less economical 35 than that necessary to the preservation of food products alone, it being also well-known that the horsepower per ton of refrigerating effect, particularly in the usual small compression plant, increases rapidly as the suction pressure is 40 lowered.

With systems employing dual evaporator temperatures designed to avoid some of the frosting troubles and dehydration, the apparatus and control become more complicated as previously noted, 45 and the refrigerating plant is still required to provide a comparatively large amount of refrigeration at uneconomically low temperatures in order to produce usable ice.

In contrast with the above, in the present invention the refrigeration to be furnished is limited substantially to the amount necessary to cool the stored food and to compensate for heat leakage, and this minimum amount itself is produced in a comparatively high and economical 55 operating temperature range. Harmful frosting and dehydration are eliminated by the means described, and at the same time a zone is provided at the proper temperature for storing commercially pre-frozen ice cubes which, due to their 60 economical production in large quantities, may normally be purchased at a price considerably less than the cost of producing them in the usual small dual-purpose refrigerator.

In addition to the above operating advantages, 65 it will be seen that the invention provides a structure which is simple, cheap, and readily manufactured and assembled.

The entire cooling assembly, being secured only to the top plate 12, may be bodily lifted therewith 70 from the top of the cabinet 11 after loosening the tubing and thermostat connections.

As an alternative construction of the evaporator units, illustrated in Figure 5, the outlet end 75 54 of each lower unit 55 instead of being connected directly to the suction header, is connected

to the inlet 58 of the overlying upper unit 57. The inlet 58 of lower unit 55 is connected to the inlet header 41a, while the outlet 59 of upper unit 57 leads into the suction header 42a. With this structure, the general operation is the same 5 as previously set forth, the refrigerant simply traversing the corresponding units of the lower and upper evaporators in series instead of in parallel.

If desired in connection with the evaporator 10 assembly structure shown in Figures 1 and 3, the inlet header 41b may be provided with valves 60 which may be initially adjusted to various settings to "balance" the distribution of liquid refrigerant to the units of the evaporator. 15

While the invention has been set forth in preferred form, it is not limited to the exact structures illustrated, as various modifications may be made without departing from the scope of the appended claims. 20

What is claimed is:

1. In a refrigerator, in combination, a main casing, a horizontal panel in said casing dividing the interior thereof into an upper and a lower chamber, a horizontal evaporator mounted on 25 said panel and spaced above the same in said upper chamber, an ice tray overlying said horizontal evaporator in heat exchange relation therewith, a pair of vertical plates suspended from said panel in said lower chamber, tubular 30 evaporators countersunk in said plates and having lateral surfaces protruding from said plates, means clamping said plates together whereby said protruding tubing surfaces are pressed together in flattened contact relation, lateral heat absorbing fins on said plates, means forming a common liquid inlet to said upper and lower evaporators, and means forming a common vapor outlet from said upper and lower evaporators. 35

2. In a dual temperature refrigerator, in combination, a main casing, a horizontal panel dividing the interior of said casing into a relatively restricted upper chamber and a relatively large lower chamber, a perforated heat conducting pan mounted on the upper side of said partition 45 and spaced therefrom, an evaporator secured to the bottom of said pan in intimate heat exchange relationship therewith, a pair of tubular uniplanar evaporator units disposed vertically in said lower chamber below said panel, heat absorbing means clamping said tubular units laterally together in flattened contact relationship, said clamping means being secured to said panel, a baffle secured to said panel and surrounding said clamping means and lower evaporator units, said baffle being open at the bottom and having lateral openings near the top thereof whereby circulation of air in said lower chamber may be promoted, means to conduct water from 50 said upper chamber into said lower chamber within said baffle, and means to distribute said water to said circulating air. 55

3. The invention claimed in claim 2 wherein said water conducting means includes perforations in said horizontal panel and wherein said distributing means comprise lateral fins on said clamping means underlying said perforations. 65

4. The invention claimed in claim 2 including a perforated ice tray removably disposed on said 70 perforated pan.

5. The combination claimed in claim 2 wherein said refrigerator includes a removable top plate and wherein said panel is secured to said plate, whereby said panel and said parts attached there- 75

- to may be removed as a unit with said plate from the top of said casing.
6. In a device of the character described, in combination, a pair of parallel tubular uniplanar evaporator units, heat conducting means partially enveloping the tubing of said units and pressing said units laterally together in flattened contact relationship, and lateral fins on said heat conducting means.
- 10 7. In a device of the character described, in combination, a horizontal panel, a perforated pan secured to said panel in spaced relation above the same, a horizontal tubular evaporator secured to the bottom of said pan in intimate heat transfer relationship therewith and spaced above said panel, a pair of uniplanar tubular evaporator members disposed vertically below said panel, means forming open fluid communications between said upper evaporator and said lower evaporator members, heat conducting members partly embracing said tubular evaporator members and pressing the same laterally against each other in flattened contact relationship, said heat conducting members being secured to said panel, lateral fins on said heat conducting members,
- 5 said panel having perforations overlying said fins, and a vertical baffle secured to said panel and surrounding said lower evaporators, heat conducting members and fins, said baffle having lateral openings near the top thereof.
8. The combination claimed in claim 7 including a perforated ice tray removably disposed in said perforated pan in heat exchange relationship therewith.
9. That method of operating a two-compartment refrigerator which comprises producing refrigeration from a common source in both of said compartments at or about the freezing temperature of water, restricting air circulation in one of said compartments, promoting air circulation in the other of said compartments, storing pre-frozen ice in said first compartment, storing articles to be refrigerated in said second compartment, and delivering moisture of condensation and/or meltage from said first compartment to the circulating air of said second compartment to increase the humidity in said second compartment.
